UNITED STATES PATENT OFFICE.

VICTOR BOGAERT, OF LEXINGTON, KENTUCKY.

DESIGN FOR A SPOON.

SPECIFICATION forming part of Design No. 31,779, dated November 7, 1899.

Application filed September 23, 1899. Serial No. 731,493. Term of patent 3½ years.

To all whom it may concern:

Be it known that I, VICTOR BOGAERT, a citizen of the United States, residing at Lexington, in the county of Fayette and State of Kentucky, have invented and produced a new and original Design for Spoons; and I do hereby declare the following to be a full, clear, and exact description of the same, reference being had to the accompanying drawings, forming a part thereof.

Figure 1 is a plan view of the spoon in a vertical position, showing the bowl or front thereof. Fig. 2 is also a plan view of the spoon in a vertical position, showing the reverse side.

As shown in the drawings, the leading or material feature of my design consists of an arrow-shaped spoon, the bowl A thereof being in the form of an arrow-head attached to

the shaft B after the fashion adopted by primitive Indian tribes. The handle is made to represent the shaft of an arrow, also showing primitive attachments, the whole of said spoon having the complete arrow effect. Otherwise the bowl and handle are left plain, as shown in both figures.

Having described my invention, what I claim as new, and desire to secure by Letters Patent, is—

The design for a spoon, as herein shown and described.

In testimony whereof I affix my signature in presence of two witnesses.

VICTOR BOGAERT.

Witnesses:

D. GRAY FALCONER,
KATIE CLARK.
